UNITED STATES PATENT OFFICE.

WILLIAM H. ELLIOT, OF ST. LOUIS, MISSOURI, ASSIGNOR TO ELLIOT FROG & SWITCH COMPANY, OF EAST ST. LOUIS, ILLINOIS, A CORPORATION.

ADJUSTABLE SWITCH-ROD.

No. 813,873.

Specification of Letters Patent.

Patented Feb. 27, 1906.

Application filed December 23, 1905. Serial No. 293,088

To all whom it may concern:

Be it known that I, WILLIAM H. ELLIOT, a citizen of the United States, residing in the city of St. Louis and State of Missouri, have 5 invented certain new and useful Improvements in Adjustable Switch-Rods, of which the following is a full, clear, and exact description, reference being had to the accompanying drawings, forming part of this specification.

My invention relates to that character of switch-rods in which an eccentric is used to provide for the lateral adjustment of the switch-point rail-sections of a railway-track 15 to shift them toward each other or away from each other in order that they may be properly brought into juxtaposition with the main-track rails when shifted thereto.

Figure I is a cross-section taken through a 20 railway-track at the location of its switch-point rail-sections and showing in elevation a switch-rod connected to the switch-rail sections in accordance with my improvement. Fig. II is an enlarged top or plan view of a 25 fragment of the switch-rod and means by which said rod is connected to a switch-point rail-section. Fig. III is a vertical longitudinal section taken on line III III, Fig. II. Fig. IV is a horizontal section taken on line 30 IV IV, Fig. III, with the switch-rod and eccentric-block shown in top or plan view. Fig. V is a perspective view of my eccentric-block.

A designates main rolls of a railway-track, 35 and B switch-point rail-sections that are adapted to be moved to the main rails, as usual.

1 designates brackets that are secured by bolts or other suitable means to the switch-point rail-sections. Each of these brackets is provided with a U-shaped arm 2, consisting of an upper member and a lower member united by a bow-shaped portion. The upper and lower members of the arm are provided 45 with circular bolt-holes 3. (See Fig. III.)

4 represents bolts that pass through the bolt-holes in the arm members of the brackets and which have applied to them nuts 5, that may be held from dislodgment by keys 50 6, passing through the bolts.

7 designates a switch-rod that is seated within the U-shaped arms of the brackets 1 between their top and bottom members. This switch-rod is provided with polygonal

apertures 8, (see Fig. IV,) which are so located in the rod as to occupy positions within the U-shaped arms when the rod is connected to the brackets 1. The polygonal apertures in the switch-rod preferably have the form of the points of a star in outline.

9 designates an eccentric-block of polygonal shape and having therein a bolt-hole 10, that is located at one side of the axis of the block. One of these blocks is utilized in each of the apertures 8 of the switch-rod. The 65 eccentric-blocks are polygonal in shape, being preferably of star form to fit within the correspondingly-shaped apertures in the switch-rod and to be held from rotation therein. I prefer to make the eccentric-blocks of star 70 shape in contour, for the reason that by doing so I am able to secure a greater degree of adjustment of the eccentric-blocks in the apertures of the switch-rod, while at the same time such angles at the points of the blocks 75 may be produced as to obviate all liability of turning of the eccentric-blocks in the switch-rod apertures.

In the practical use of an adjustable switch-rod made in accordance with my invention the switch-rod is readily adjusted 80 relative to the switch-point rail-sections or the switch-point rail-sections relative to the switch-rod by simply removing the bolts 4, that pass through the U-shaped arms of the 85 brackets and the eccentric-blocks, when the switch-rod may be withdrawn from the brackets and the eccentric-blocks removed and reinserted in altered positions, according to the degree of adjustment that it may be desired 90 to make. In so adjusting the eccentric-blocks the bolt-holes therein are moved into varied positions to space the bolt-holes in the pair of eccentric-blocks either more remote from each other or bring them closer together, 95 thereby varying the positions of the switch-point rail-sections, when the brackets carried thereby are again connected to the switch-rod by the bolts passing through the bracket-arms and the eccentric-blocks.

While I have described my switch-rod as provided with a pair of apertures and a corresponding number of eccentric-blocks seated therein and adapted to receive the attachment of the two switch-point rail-sections of a 105 railway-track, it is obvious that if desired only a single aperture may be made in the switch-rod and a single eccentric-block used

for the purpose of securing adjustment of one switch-point section, and the second switch-point section may be connected to the switch-rod in any suitable manner without making 5 use of my improvement.

I claim as my invention—

1. The combination with a pair of railway switch-point rail-sections, of a bracket connected to one of said switch-point rail-sections, 10 a switch-rod having a polygonal aperture therein, an eccentric-block seated in said polygonal aperture, and a bolt passing through said bracket and eccentric-block, substantially as set forth.
- 15 2. The combination with a pair of railway switch-point rail-sections, of a bracket connected to one of said rail-sections, a switch-rod having a star-shaped aperture therein,

an eccentric-block of star shape fitting in said aperture, and a bolt passing through said 20 bracket and said eccentric-block, substantially as set forth.

3. The combination of a pair of railway switch-point rail-sections, a bracket secured to one of said rail-sections and having a **U**- 25 shaped arm, a switch-rod fitting within the **U**-shaped arm of said bracket and having a polygonal aperture therein, a polygonal eccentric-block seated in said polygonal aperture, and a bolt passing through said **U**- 30 shaped arm and said eccentric-block, substantially as set forth.

WILLIAM H. ELLIOT.

In presence of—
E. S. KNIGHT,
BLANCHE HOGAN.
